UNITED STATES PATENT OFFICE

JOHN A. HALE, OF TRIPOLI, IOWA

SANITARY FLOOR FOR BROODERS

Application filed January 12, 1928. Serial No. 246,308.

This invention relates to brooders, and particularly to what may be termed a false floor therefor by which sanitation in the brooder is very greatly assisted.

5 The general object of the invention is to provide a floor which is so constructed that it will promote health and sanitation by eliminating spread of disease and securing not only cleanliness of the chicks but cleanliness 10 of the feed and water, and which will further eliminate crowding and smothering of the chicks.

A further object is to provide a unitary structure including a sectional floor of wire 15 netting, a side wall with which this wire netting floor may be engaged and supported at its margin from the floor of the brooder house, the sections of wire netting being provided with legs extending down to the floor 20 of the brooder house so that the wire netting floor may be firmly supported throughout its area, the floor being made of wire netting of such sized mesh as will permit the droppings to fall through or be forced by the chicks 25 moving over the floor, such mesh, however, being of such size that it will prevent the chicks from getting their legs or feet through this floor of wire netting.

A still further object is to provide a floor 30 of this character made in sections so that it may be compactly nested for transportation and which is provided with depending legs so that the false floor, as it were, may be disposed within the brooder and supported 35 from the true floor thereof.

Other objects will appear in the course of the following description.

My invention is illustrated in the accompanying drawings, wherein:—

40 Figure 1 is a top plan view of a brooder floor constructed in accordance with my invention;

Figure 2 is a side elevation thereof;

45 Figure 3 is a fragmentary vertical section through the floor showing the watering pan;

Figure 4 is a fragmentary vertical section showing one of the feeders;

50 Figure 5 is a detail vertical section at the intersection of two sections of the floor;

Figure 6 is a perspective view of the bracket for supporting a water or feed pan; Figure 7 is an elevation of one of the feet.

Referring to these drawings, 10 designates the sanitary floor, which is formed of wire 55 mesh preferably of half inch gauge, though a smaller or larger gauge might be used. This floor is preferably made in sections and I have illustrated it as made in six sections A, B, C, D, E, and F. Each of these sections 60 has an outside wall 11 of wire network which is joined to the sanitary floor, as will be later described.

Each section along its inside margins is formed, as shown in Figure 5, by forming a 65 depending flange 10^a in the wire network and disposing this flange within an approximately U-shaped strip 12 of sheet metal. These depending binding strips 12 abut against each other and are held in engagement with each other by small stove bolts 13. Thus these sections may be readily connected to or disconnected from each other. The sections, when put together, are preferably octagonal in plan. 75

Disposed between the side wall 11 of wire network and the floor sections 10 are sheet metal members 14. These are rebent upon themselves at 11^a, as shown in Figure 3, at their upper edges to receive the lower margins of the wire network 11, and at their lower margins each sheet metal section 14 is bent inward at 15 and then rebent upon itself so as to provide a recess to receive the flange of a supporting bracket, as will be 85 later stated, and the margin of the sheet metal 14 is then again bent inward, as at 16, to form a recess to receive the floor 10. The sheet metal 14 is cut out just above the floor, as at 14^a, to provide openings in each side wall for 90 the reception of water and feed receptacles.

Preferably a more or less centrally disposed opening 17 is formed in the sanitary floor through which the heater may extend. This opening will vary in shape according to 95 the type of heater. Legs 18 angular in cross section are attached to the under face of the floor and are intended to be fastened to the sectional strips 12 at the junctions thereof and at the extremities where needed. These 100

legs will be approximately one and a half inches long. The bolts 13 fasten these legs to the strips 12.

The brackets 19, as shown in Figure 6, are made of sheet metal and angular in form and the outwardly projecting portion of each bracket has an upwardly extending flange 20. At its inner end each bracket is bent straight downward, as at 21, to engage the floor of the hen house or brooder house and then extends straight upward, as at 22, to a point just beneath the opening 14^a, and then is bent downward and then outward, as at 23, to engage in the recess formed between the plies of sheet metal 15 and 16. Each bracket has a downwardly extending side web 24 whose upper end is flanged at 25 and riveted to the bracket 19 and this web 24 is provided with an outer flange 26 and a base flange 27 to rest upon the floor. The tray 28 may be made of metal or any other suitable material and is supported upon the corresponding bracket 20, this tray being provided with a stop 28^a which prevents the tray from being inserted too far into the opening 14^a but will permit the tray to have its inner end inserted through the opening sufficiently to permit the chicks to drink or feed. There may be as many of these trays as desired.

30 The feed containers 29 shown in Figure 4 are somewhat different in form from the water containers, in that they have an upward extension 30. The heel of the container is provided with a slanting false bottom 31 so as to direct the feed forward, and preferably the tray is formed with a partition three inches from one end in order to make a separate receptacle for grit or other needed food, or in other words this tray may be separated into compartments so that different kinds of feed may be supplied. This feeding tray or container has a metal brace 32 which extends downward from the inclined bottom 27 and engages the bracket 20 and supports the tray.

45 In order to remove the feeding and watering trays, it is only necessary to lift them up at the back and then withdraw them, the upwardly extending flange 20 of the bracket acting to lock the trays in place.

50 The advantages of this brooder floor will be obvious from what has gone before. It is practically self-cleaning, as the droppings that do not fall through the wire mesh are quickly forced through by the chicks moving around over the floor. Water and feed cannot be scratched out and become unsanitary, as what little is wasted drops through the wire mesh out of the chicks' reach. The feed and water always remain clean because most 55 of the area of the water and feeding trays are exterior to the side wall and out of the chicks' reach, only enough of these trays protruding through to the inside to allow of access for feeding and drinking. The chicks cannot crowd in on this floor, as there are no

square corners for them to congregate in, and even if the chicks did pile up the under chicks will be perfectly safe from any danger of smothering inasmuch as the wire mesh underneath gives free circulation of air.

As there is no litter to clean up and replenish and since through the construction of the floor it will be only necessary to clean out the droppings beneath the floor every fifteen or twenty days, much time and labor will be saved. Furthermore, the feeders and waterers will be easily accessible without the necessity of walking amongst the chicks. In my observation about 90% of the spread of disease from infected chicks to healthy chicks is caused through the healthy chicks coming in contact with and picking at the droppings of diseased chicks and also through eating food that has become contaminated in the litter and by drinking contaminated water. This will be entirely obviated by this wire mesh floor. I contemplate the use of paper beneath the wire mesh floor to catch the droppings, as this paper may be readily removed and burned when dirty.

The floors obviously will be made of different sizes to conform to different size brooders and, of course, the shape of the floor will be made to conform to the shape of the brooder with which it is to be used. Where a heating element with a chimney is used, the floor is to be provided with an opening 17, as previously stated, but for brooders using electrical heat there would not necessarily be any opening through the floor. A medium size floor will have a dimension of eight feet across each way.

Obviously many changes might be made in the details of construction and arrangement of parts without departing from the spirit of the invention as defined in the appended claims.

I claim:—

1. As an article of manufacture, a floor for brooders formed of a plurality of sections of wire mesh, the wire mesh being of sufficient gauge to permit droppings to pass therethrough, the exterior edges of the sections having supporting means to which the sections are attached, the interior margins of the sections having supporting metallic strips to which the section is attached, the supporting strips of one section being adapted to be bolted to the supporting strips of an adjacent section, the floor being provided with a plurality of depending legs.

2. A floor for brooders formed of sections of wire netting, the wire netting being of sufficient gauge to permit droppings to pass therethrough, each section having downwardly extending marginal portions whereby one section may be bolted to the next and each section having an upstanding marginal wall, said wall being apertured for the passage of a feeding or watering receptacle, a

bracket engaged with the margin of the wall, the bracket extending downward below the floor and outward and having an upstanding outer end, receptacles adapted to be disposed upon said brackets, each receptacle having a portion thereof, insertable through the aperture in the wall, and means on the receptacle preventing inward movement of the receptacle with reference to the wall.

3. A floor for brooders formed of wire mesh, the wire mesh having a gauge sufficient to permit droppings to pass therethrough, the floor being formed of sections detachably engaged with each other, each section having a plurality of downwardly extending legs whereby the sections may be supported, the exterior of the floor having an upstanding wall, brackets attached to the floor at a plurality of points, the upstanding wall being slotted opposite said brackets, and feeding and watering devices having portions adapted to be inserted through said slots, the greater portion of each device being exterior to the wall and being supported by brackets.

4. As an article of manufacture, an open-work false floor for brooders having means whereby it may be supported above the usual brooder floor, the floor having an upstanding sheet metal marginal wall extending inward at its lower margin and folded to form an outwardly opening horizontal recess and an inwardly opening horizontal recess, the last named recess receiving the margin of the false floor, and supporting members each having a horizontal flange disposed in the first named recess.

5. As an article of manufacture, an open-work false floor for brooders formed in sections, the sections having means whereby they may be engaged with each other and each section having supporting legs, the floor having an upstanding marginal wall having food tray receiving openings, members constituting legs detachably engaged with the false floor and disposed immediately below said openings, and food receptacles disposed in said openings but removable therefrom and supported by said members.

6. As an article of manufacture, an open-work false floor for brooders having means whereby it may be supported above the usual brooder floor, the floor having an upstanding sheet metal marginal wall having food receptacle openings, the wall below said openings being folded to form an outwardly opening horizontal recess and an inwardly opening horizontal recess, the last named recess receiving the margin of the false floor, supporting members each having a longitudinal flange disposed in the first named recess, and food receptacles disposed through said openings and resting upon said supporting members.

7. As an article of manufacture, an open-work false floor for brooders having means

whereby it may be supported above the usual brooder floor, the floor having an upstanding sheet metal marginal wall having food receptacle openings, the wall below said openings being folded to form an outwardly opening horizontal recess and an inwardly opening horizontal recess, the last named recess receiving the margin of the false floor, supporting members, each having a longitudinal flange disposed in the first named recess, and food receptacles disposed through said openings and resting upon said supporting members, each supporting member having an upwardly extending flange at its outer end preventing the direct outward movement of the food receptacle.

8. As an article of manufacture, an open-work false floor for brooders, the floor being formed in sections detachably engaged with each other, each of said sections having an upstanding sheet metal marginal wall having an opening for the reception of a food receptacle, the sheet metal wall extending below said opening and then being formed to provide an outwardly opening horizontal recess and an inwardly opening horizontal recess, the last named recess receiving the margin of the false floor section, supporting brackets each formed of sheet metal bent to provide a horizontal portion and a vertical inner portion having an inwardly projecting flange adapted to be received within the first named recess, a flange supporting web attached to said outwardly projecting portion of said brackets, and food receptacles adapted to be disposed through said openings and supported by said brackets.

In testimony whereof I hereunto affix my signature.

JOHN A. HALE.
